UNITED STATES PATENT OFFICE.

LOUIS YENTIS AND WILLIAM LANGE, OF NEW YORK, N. Y.

LAMP-SHADE HOLDER.

Application filed April 14, 1924. Serial No. 706,443.

To all whom it may concern:

Be it known that we, LOUIS YENTIS and WILLIAM LANGE, citizens, respectively, of the United States and Germany, residing 5 in New York city, county of New York, borough of Manhattan, and State of New York, have invented new and useful Improvements in Lamp-Shade Holders, of which the following is a full, clear, and ex-10 act specification.

Our invention relates to lamp shade holders and refers particularly to shade holders of a revoluble, or folding character.

Lamp shade holders suitable for use with 15 electric bulb standards comprise a plurality of uprights attached to the lamp standards and capable of carrying a lamp shade.

Devices of this character are, therefore, somewhat bulky when attached to the lamp 20 standard and because of their light construction are usually liable to be bent, or broken, during shipment unless packed with exceptional care.

In the employment of electric light bulbs 25 careful wiring with the bulb socket is necessary and lamp shades of a permanent and unfoldable character interfere with the ready and careful wiring of the bulb socket, because the uprights of the holder prevent, or 30 interfere with, an easy approach to the lamp socket.

This objection is emphasized by the fact that the shade holder is usually fixedly attached to the lamp standard by the socket itself, and hence, the latter must be wired 35 while the holder is in position.

The device of our invention overcomes all 40 of the described, and other, objectionable features and presents a means whereby an effective and efficient lamp shade holder may be employed and fixedly attached to a lamp standard without interference with the easy and proper wiring of the lamp socket.

Our device also possesses the valuable feature of occupying but little space in packing, coupled with practical protection from 45 injury and damage during shipment.

A consideration of our specification and 50 the accompanying drawings will explain and indicate the valuable attributes of the device of our invention.

In the accompanying drawings, illustrating 55 the device of our invention, similar parts are designated by similar numerals.

Figure 1 is a plan view of our device in operative position, partly in section for clearness of description.

Figure 2 is a plan view of Figure 1 in 60 folded position.

Figure 3 is a perspective view of the shade holder of Figure 1.

Figure 4 is a perspective view of the base of Figure 1.

Figure 5 is a broken vertical section of a 65 modification of our device.

The particular form of the device of our invention, illustrated in Figures 1, 2, 3 and 70 4, comprises a base 10 having the two upwardly extended end members 11, 11. Each end member 11 has a vertically elongated opening 12. The upper portion of each end member 11 has two outwardly extended wings 13, 13. The base 10 has a threaded opening 14 through which the base 15 of 75 the lamp socket 16 can be threaded into a corresponding opening in the top of the standard 17, thus firmly positioning the base member thereto.

The shade frame 18, formed so as to extend 80 around the lamp 19, has two inwardly extended ends 20, 20, each having a reduced portion 21 and a terminal member 22.

The terminals 22, 22 are of such size and 85 shape as to allow them to be introduced through the openings 12, 12 when the shade holder 18 is in a horizontal position, but being capable of passage therethrough when the shade holder is in vertical position.

The shade holder, therefore, can be affixed 90 to the base ends 11, 11 by such horizontal introduction followed by a vertical inclination of the holder.

The shade support 18 is made of steel, or 95 some other resilient material, so that when it is in vertical position it will be placed between the wings 13, 13 and thus held in position from which it is removable by revolution only by the exertion of sufficient pressure to spring it out of the recess formed by the wings 13, 13.

The shade holder 18 carries the upwardly extended threaded member 23 capable of receiving a lamp shade.

We prefer to have the relationship between the standard 17 and the shade support 18 of such a character as to allow the placement of the latter free from abutment with the surface upon which the standard 17 rests when the shade support is in its utmost 100 105 110

2 downward position, as shown in Figure 2.

It will thus be seen that the shade support can be folded, when desired, without disengagement with its base, into a position 5 allowing of absolute freedom of approach to the device for purposes of wiring the lamp socket and that it adapts itself particularly to a minimum amount of space for packing purposes, coupled with safety from 10 breakage.

The modification of our device, illustrated in Figure 5, is similar to that above described with the exception that the shade support 18 is pivotally attached to the base 15 ends 11 at 24, 24, thus allowing revolution without disengagement.

We do not limit ourselves to the particular size, shape, number or arrangement of parts, as shown and described, as these are 20 given simply as a means for clearly defining our invention.

What we claim is:—

1. In a lamp shade holder, in combination, 25 a base capable of fixment to a lamp standard, oppositely opposed upwardly extended ends to said base, a locking means carried by the ends and a shade support pivotally carried by said ends capable of removal from jointure with the base ends when the support 30 is in a horizontal position and capable of resilient placement within said locking means when it is in vertical position.

2. In a lamp shade holder, in combination,

a base capable of fixment to a lamp standard, 35 opposed upwardly extended ends to said base, each end having a vertically elongated opening therein, a locking means carried by each end and a shade support having elements capable of placement through the end openings when the support is in a horizontal position but incapable of placement therethrough when the support is in a vertical position, said support being capable of 40 resilient placement within the locking means when it is in vertical position.

3. In a lamp shade holder, in combination, 45 a base having an opening therein capable of receiving an electric bulb socket attaching the base to a lamp support, opposed upwardly extended ends to said base, each end having a vertically elongated opening therein, a plurality of outwardly extended spaced wings carried by each end and a shade support 50 the lower free ends of which are capable of passage inwardly through the end openings when the support is in horizontal position and incapable of removal therefrom when the support is in vertical position, the support being capable of resilient placement 55 between the end wings locking the support 60 in a vertical position.

Signed at New York city in the county of New York and State of New York this 8th day of April, 1924.

LOUIS YENTIS.
WILLIAM LANGE
